UNITED STATES PATENT OFFICE.

LELLA W. KNIGHTON, OF PORTLAND, OREGON.

DESIGN FOR A TOY BANK.

SPECIFICATION forming part of Design No. 36,766, dated February 2, 1904.

Application filed December 29, 1903. Serial No. 187,073. Term of patent 7 years.

To all whom it may concern:

Be it known that I, LELLA W. KNIGHTON, a citizen of the United States, residing at Portland, in the county of Multnomah and State of Oregon, have invented a new, original, and ornamental Design for Toy Banks, reference being had to the accompanying drawings for disclosure thereof, in which—

What I claim as new, and desire to secure by Letters Patent, is—

The ornamental design for a toy bank, substantially as herein shown.

LELLA W. KNIGHTON.
